ATTORNEY

UNITED STATES PATENT OFFICE.

WILLIAM E. BOCK, OF CHICAGO, ILLINOIS.

LIGHT BULB.

Application filed July 19, 1922. Serial No. 576,076.

To all whom it may concern:

Be it known that I, WILLIAM E. BOCK, a citizen of the United States, residing at Chicago, in the county of Cook and State of Illinois, have invented new and useful Improvements in Light Bulbs, of which the following is a specification.

This invention relates to vacuum-tube lights or lighting, and an object of the invention is to provide a vacuum-tube bulb having contacts spaced at its opposite ends which are adapted to be connected in circuit with a suitable energizing source for permitting the passing of electric currents through the vacuum-tube from one contact to the other for the purpose of creating light, the brilliancy of which may be controlled by the frequency of the current passing therethrough.

Heretofore, in vacuum-tubes of this type, various types of contacts such as exterior or interior caps have been provided and in the present invention, a simplified practical tube structure has been devised in which an electrode has been provided which is alike suitable for use as a positive or as a negative electrode which may therefore be employed for both electrodes of the lamp operated by alternating currents.

Other objects of the invention will appear in the following detailed description taken in connection with the accompanying drawing wherein:

Fig. 1 is a side elevation of the improved vacuum lighting tube.

Fig. 2 is a fragmentary longitudinal section through the tube.

Referring more particularly to the drawings, the improved lighting tube comprises a vacuum-tube 1, preferably cylindrical in shape and which may be made in any desired length. The ends of the tube 1 are rounded as clearly shown in Fig. 2 of the drawings and having inwardly extending nipples 2 formed thereon in which the electrodes 3 are molded. The electrodes 3 comprise straight wires of any desired material and their inner ends project short distances beyond the inner ends of the nipples 2, while their outer ends are flush with and may engage or be formed upon the substantially frusto conical contacts 4 which are carried by the cap

structures 5. The cap structures 5 include metal shells or caps 6 which are cemented in any suitable manner to the tube 1 as shown at 7 and the contacts 4 are insulated from the metal caps 6 by shells 8 of insulation. The contacts 4 have binding screws 9 formed thereon, on which suitable binding nuts 10 are threaded, to permit connection of electric conducting wires 11 to the contacts at the opposite ends of the tube 1.

It is, of course, to be understood that the invention may be constructed in other manners and the parts associated in different relations and, therefore, I do not desire to be limited in any manner except as set forth in the claims hereunto appended.

Having thus described my invention what I claim is:

1. A vacuum lighting tube including a tube of transparent insulating material having a rounded end, a nipple formed upon the axis of the rounded end and extending a short distance into the tube, an electrode molded in said nipple and projecting a short distance into the tube beyond the inner end of the nipple, a cap mounted upon the end of said tube, the inner end of said cap embracing the walls of the tube, means embracing the end of the tube and spacing the end of the cap therefrom, a frusto-conical contact carried by and insulated from said cap, said contact engaging the electrode and a binding post carried by the apex of the contact.

2. A vacuum lighting tube including a tube of transparent insulating material having a rounded end, an electrode fixed to the end of the tube and projecting a short distance into said tube, a cap mounted upon the end of the tube, the inner end of said cap embracing the walls of the tube, means spacing the end of the cap from the end of the tube said cap having a central opening in the closed end thereof, a frusto-conical contact abutting the end of the tube for engagement with the electrode, said contact extending through the opening in the cap and insulated therefrom and a binding post carried by the apex of said contact.

In testimony whereof I affix my signature.

WILLIAM E. BOCK.
